UNITED STATES PATENT OFFICE

2,599,325

CONDUIT CONSTRUCTION

Lawrence H. Fritzberg, Minneapolis, Minn.

Application November 22, 1946, Serial No. 711,775

4 Claims. (Cl. 138—28)

1

This invention relates to conduit constructions, and more particularly to conduits adapted for use in heat exchange units.

One of the objects of the invention is to provide a conduit structure or an attachment for conduits wherein means is provided to prevent the conduit from being ruptured from the expansion of liquids therein due to variation in temperatures. For instance cooling coil heat exchangers which utilize water as an internal cooling medium in a tube are used in air conditioning systems. Such coils are frequently subjected to abnormally low temperatures when cold outside air is taken into the system. The freezing of the water and rupturing of the tube or pipes results through the omission of preheaters on their failure, failure of the heating medium or stratification of air at freezing temperatures.

Ordinarily to protect these coils against freezing it is necessary to take the coils apart and drain them, or blow them out or add a non-freezing solution. Such methods provide protection only when done carefully and thoroughly, and even then may not give proper protection, since in the case of adding a non-freezing solution, distribution may not be proper and the desired amount of non-freezing solution may not reach all parts of the coil. Blowing out the coils also is not entirely effective because of capillary attraction within the tube.

I propose to provide a compressible member which will allow for the expansion of water upon freezing so that the strength of the tubes or pipes will not be affected. The compressible member or its support is further so constructed and arranged as to agitate the liquid in the conduit to some extent as it flows through them, and it has been found that I can use a lower liquid velocity to secure the same heat transfer as that of a plain tube or other conduit at a higher velocity.

The above and other objects and advantages of the invention will more fully appear from the following description made in connection with the accompanying drawings, wherein like reference characters refer to the same parts throughout the views, and, in which:

Figure 1 is a view partially in side elevation and partially in longitudinal vertical section of an embodiment of the invention installed in a tube or other conduit;

Figure 2 is a transverse vertical sectional view of the structure of Figure 1;

Figure 3 is a view partially in side elevation and partially in longitudinal vertical section of another form of the invention;

2

Figure 4 is a transverse vertical section through the structure of Figure 3;

Figure 5 is a view partially in side elevation and partially in longitudinal vertical section of a third form of the invention; and

Figure 6 is a transverse vertical sectional view through the structure of Figure 5.

In Figures 1 and 2 there is shown a conduit 7 which, if used in an ordinary heat exchange unit, would be a piece of tubing. Within the conduit 7 is a spiral element 8 made up of a pair of spaced metal strips 9 lying at either side of a thicker strip of compressible material 10 which may be sponge rubber, soft cork or any other suitable compressible substance which would be unaffected by the liquid passing through the conduit 7. It should be noted that the spiral unit 8 is so formed that it closely fits the interior of the conduits 7 and the spirals are relatively open so that liquid can flow relatively freely through said conduit while at the same time a certain amount of turbulence or agitation is imparted thereto.

In the event the liquid such as water which passes through the conduit 8 is subjected to less than normal temperatures for which the apparatus is designed and the liquid freezes, the expansion thereof will compress the yieldable material 10 and press the metal side strips 9 inwardly toward each other. The degree of normal compressive movement of the material 10 obviously would be ascertained so that if the water in the conduit 7 should freeze solid there would be sufficient compressibility of the material 10 to prevent rupturing strain on the conduit. The metal strips 9 are provided to hold the compressible member in proper shape in the conduit.

Not only does the element made up of the members 9 and 10 eliminate rupturing due to expansion when the liquid freezes, but is sufficiently agitates the liquid passing through the conduit to increase the internal heat transfer of the liquid through the conduit and it permits a lower velocity of liquid to compensate for the increased pressure drop due to friction as compared to a plain conduit without a compressible member therein.

In Figures 3 and 4 there is shown a conduit 11 within which is located a flattened hollow elongated tubular element 12 between the side walls 50 of which is positioned an elongated rubber element 13. The outer sides of the flattened tubular element 12 are provided with oppositely directed and staggered angular vanes 14 which are directed outwardly and in a direction of flow of liquid through the conduit, such direction being

indicated by arrows. Extending outwardly from the outer edges of the vanes 14 are legs 15 which, as best shown in Figure 4, are adapted to position the flattened tubular element 12 centrally in the conduit 11.

The flattened tubular element 12 is capable of being compressed when liquid in the conduit 11 expands in freezing and as the sides of the tubular element 12 are compressed toward each other they will in turn press the elongated rubber filler 13 somewhat in the manner of the pressure of the metal strips 9 lying on either side of the compressible element 10 in Figures 1 and 2. The vanes 14 create a turbulence or an agitation of liquid flowing through the conduit, and the legs 15, as stated, are provided to position the unit in the conduit approximately in the center thereof.

In Figures 5 and 6 I show a conduit 16 having one of a series of frusto-conical helices 17 therein, the base 18 of the helix being approximately as large as the inner diameter of the conduit 16. It is preferred that the helix base 18 be capable of yieldable construction so that it will closely fit the inside of the pipe and may be adapted for pipes of slightly varying diameters. The upper end 19 of the helix 17 is the smaller end and forms an aperture through which an elongated compressible rod-like element 20 extends, the compressible element having a stiffening wire 21 passing through its center as shown. It is intended that the helical support 17 be placed at suitable intervals to maintain the compressible rod-like element 20 in the approximate center of the conduit 16.

The rod-like element 20 permits expansion of the freezing liquid without damage to the conduit and the helical support 17 for said rod-like element 20 not only serves as a support but as means for creating agitation or turbulence of liquid flow through the conduit for the purpose described above.

From the foregoing description it will be seen that I have provided a unit which is insertable in a conduit or combine of such a unit and a conduit which allows for expansion of a freezing liquid inside the conduit without damage thereto. The uncompressed bulk of the compressible element so limits the cross sectional flow area of the conduit that when liquid therein freezes and expands the compressible element will be reduced in size and the walls of the conduit will remain undamaged. It is also clear from the description above that the entire unit inserted in the conduit is so constructed that it will create a turbulence of flow which increases the internal heat transfer capacity of the liquid as it passes through the conduit.

It will, of course, be understood that various

changes may be made in the form, details, arrangement and proportions of the various parts without departing from the scope of my invention.

5 What I claim is:

1. In a conduit construction, a conduit section through which a liquid is adapted to pass, a flattened hollow tubular element lying generally longitudinally in said conduit, the walls of said element being flexible inwardly toward each other, and a compressible material placed within the tubular element, said element having outwardly directed vanes extending in the direction of fluid flow to agitate fluid flowing in the conduit, at least some of the vanes terminating in leg members to support the element in the conduit.

2. A conduit construction according to claim 1 in which the vanes are oppositely directed and staggered, the legs extending outwardly from the outer edges of the vanes to contact the inner walls of the tubular element.

20 3. A conduit construction according to claim 1 in which in cross-section one wall of the element is convex and the opposite wall of the element is concave.

3. A device for use in a liquid conduit which comprises a unit adapted to be placed in the conduit and having a portion thereof composed of an elongated mass of compressible material, a resilient relatively rigid framing for the compressible mass comprising a flattened, hollow tubular element enclosing the mass and having outwardly directed vanes to agitate fluid flowing in the conduit, the compressible mass filling only a portion of the space within the element, and support members to support the framing in place within the conduit.
